NEON TUBE CONTROL APPARATUS

Filed May 10, 1951

UNITED STATES PATENT OFFICE

2,673,341

NEON TUBE CONTROL APPARATUS

Richard E. Davies, Williams, Ariz.

Application May 10, 1951, Serial No. 225,596

2 Claims. (Cl. 340—343)

1

This invention pertains to neon tube control apparatus, and more particularly the invention is directed to apparatus for progressively illuminating and extinguishing a neon tube with novel control apparatus which particularly protects the power transformer for the neon tube.

One of the objects of this invention is to provide an apparatus for progressively illuminating different lengths of a neon tube and then extinguishing said tube either progressively or instantaneously while at the same time protecting the operation and efficiency of the power transformer for the neon tube.

Another object of this invention is to provide an improved control apparatus for successively illuminating different portions of a neon tube to give the effect of a rise and fall of the light in the tube from zero to maximum and return.

Still another object of this invention is to provide a control apparatus for a neon tube in which a tube is progressively lighted in step by step fashion to full illumination and extinguished while at the same time maintaining a substantially constant load on the high potential power transformer for the neon tube.

Still another object of this invention is to provide a control apparatus for successively differentially controlling a pair of neon tubes from a full lit position of one tube and an out position of the other tube to different stages of illumination, while at the same time maintaining a substantially constant load on the high potential power transformer for the neon tubes.

Further features and advantages of this invention will appear from a detailed description of the drawings in which:

Fig. 1 is a schematic diagram illustrating one form of neon tube control apparatus for progressively operating the illumination of a neon tube.

Referring to the embodiment of Fig. 1 there is shown a pair of substantially identical neon tubes 10 and 11, the tube 10 having end terminals 12 and 13 and intermediate terminals 14, 15, and 16 while the tube 11 has the end terminals 17 and 18 and the intermediate terminals 19, 20, and 21. The object of this arrangement is to successively illuminate different sections of the neon tube 10 so that from a non-lighted condition the tube will be illuminated from 12 to 14 and then 12 to 15 and then 12 to 16 and finally its full length from 12 to 13 terminals. The object then is to repeat this operation in the opposite direction with the tube burning completely from 12 to 13 then from 16 to 12 then 15 to 12 and then finally 14 to 12 after which the tube is extinguished. To do this operation directly with the single tube 10 from a power transformer or high potential transformer preferably of a leakage-resistance type such as indicated generally at 60

2

22 would result in increasing the effect on the secondary winding 23 of the transformer 22 and then reducing it again to zero, such an operation, as is well known in the art, resulting in overheating, damage and inefficient operation of the transformer 22.

Applicant therefore provides a novel arrangement of the second tube 11 of substantially identical character and number of terminals to that of the tube 10 and to control the application of power from the transformer 22 to both of the tubes simultaneously in a differentially controlled manner by novel control mechanism now to be described.

15 The transformer 22 is energized from a suitable power supply line such as the leads L1 and L2 there being provided in one of the lines such as the line L1 a main cutoff switch 24. Lines L1 and L2 are connected to the primary 20 winding 25 of the transformer 22 so that when the switch 24 is closed the secondary winding 23 will be constantly energized. One terminal of the secondary winding 23 is connected through a lead 26 to the one end terminal 12 of the neon tube 10 while the other terminal of the secondary winding 23 is connected through a lead 27 to the end terminal 17 of the neon tube 11. The outer terminals 13 and 18 of the neon tubes 10 and 11 respectively are connected together by 25 a common lead 28.

Intermediate the tubes 10 and 11 is mechanically operated switching gear comprising a central rock shaft 29 which is electrically connected through a flexible wire 30 to the lead 28 so that 35 current from the line 28 may be at all times applied to the rock shaft 29 during its rocking motion. Fixed to rotate with the rock shaft 29 are the contact arm actuating levers 31, 32, 33, and 34 for the neon tube 10 and the contact arm 40 actuating levers 35, 36, 37, and 38 for the neon tube 11. Journaled for free rotation on the rock shaft 29 and electrically connected thereto are the contact arms 39, 40, 41, and 42 associated with the respective actuating lever members 31 through 34 inclusive and the contact arms 43, 44, 45, and 46 similarly journaled on the rock shaft 29 and associated with the respective actuating levers 33 through 38 inclusive. Resilient tension spring means 47 are interconnected between the actuating levers 31 through 38 inclusive and the contact lever arms 39 through 46 inclusive so that the contact arms are normally held in contact with the respective actuating lever arms such as best shown by the lever arm and contact arm arrangement 35—43 in Fig. 1. On the outer ends of the contact arms are provided suitable contacts A, B, C, and D for the neon tube 10 and E, F, G, and H for the neon tube 11 which engage mating contacts 48, 49, 50, and 51 respectively connected to the terminals 12, 14, 15, and 55 55

16 of the tube 10, and the mating contacts 52, 53, 54, and 55 respectively connected to the terminals 17, 19, 20, and 21 of the neon tube 11. Thus as rock shaft 29 is rotated to one direction or the other the respective contacts A through H are engaged with contacts connected to the various terminals of the neon tubes 10 and 11 as described.

In order to give a progressive contacting and closing of the terminals A through H the various actuating arms such as 31 through 34 are clamped to the shaft 29 in different rotary indexed positions on the shaft as are the members for the tube 11. As shown in Fig. 1 the arms 38, 37, 36, and 35 are progressively arranged at greater distances away from the respective contact terminals 55, 54, 53 and 52 so that as the rock shaft 29 is rotated, counterclockwise as seen in Fig. 1, the contact H will first engage then G, F, and finally E with their respective contacts. At the same time the interconnecting spring mechanism 47 between the actuating lever arms and the contact arms allows the terminals on the other side to be all fully engaged while still allowing overtravel of the rock shaft 29 to further manipulate the other set of contacts.

In order to rock the shaft 29 back and forth for successively engaging and disengaging the contacts just described there is provided a main driving motor 56 which is suitably connected to the lines L1 and L2 so as to be under the control of the disconnect switch 24 as illustrated in Fig. 1. The motor 56 has an output shaft 57 upon which is connected a suitable crankshaft 58 having a crank pin 59 to which is connected a connecting rod 60 which in turn is connected through a pivot pin 61 to an actuating lever arm 62 fixed on a shaft 63 connected through a suitable insulator 64 to the rock shaft 29 so that operation of the motor 56 will oscillate the shaft 29 back and forth in rocking motion from the position 62a to the position 62b, as best seen in Fig. 1.

The operation of this arrangement is as follows: With the rock shaft 29 swung to one side fully, such as at 62a, all of the contacts A, B, C, and D are closed while all of the contacts E, F, G, and H are open so that the electric current then flows from the line 26 from the transformer 22 to the terminal 12 and then to the contact 48 and contact A through the rock shaft 29 and the flexible wire 30 to the lead 28 which in turn connects power to the outer terminal 18 of the neon tube 11, the other end of the tube 11 being connected through its terminal 17 and the lead 27 back to the transformer 22. At this time with all of the contacts A, B, C and D closed the neon tube 10 is wholly shorted out and inoperative. As the rocking motion proceeds from position 62a toward the position 62b contact H closes while contact A opens while the remaining contacts B, C and D are closed and E, F and G are open. In this situation current then flows from the transformer through line 26 to terminal 12 of the neon tube 10 to the terminal 14 and then to the contact 49 and contact B which is closed to connect to the rock shaft 29 and then out through contact H and contact 55 to terminal 21 of the neon tube 11 where the current completes itself to the end of the tube at the terminal 17 and then back through the lead 27 to the transformer 22. It is to be noted that under this contact arrangement that there is still the substantially same length or resistance of total neon tubes applied to the secondary winding of the transformer 22; 75

namely, that portion of the tube 10 from terminals 12 to 14 which is substantially the same as that portion of the tube 11 extinguished from 18 to 21.

The above operation continues for the respective contacts B and G closing and for C opening and F closing and for finally D opening and E closing, when the latter of which takes place the neon tube 11 then being fully shorted and discharged and inoperative while the full length of the tube 10 is then in operation. It will thus be noted that at all times substantially the same amount of resistance or load from neon tube operation is applied to secondary winding 23 of the transformer 22. Further it will be noted that any one of the tubes such as the tube 10 will appear to constantly rise in its light in the tube to the top and then drop back again to the bottom simulating the effect of a rising and falling thermometer or the like so as to create great selling and advertising appeal while at the same time providing an operating mechanism maintaining a constant load on the power supply transformer 22. Obviously both tubes 10 and 11 may be placed in operation simultaneously on each side of a suitable sign box which may readily house the mechanical switching gear described so that viewed from any one side or the other this simulative effect of the rise and fall of the neon tube light is obtained. Further it is highly practical to color one of the tubes dark so that no effect is produced by it so that the single tube gives the rise and fall effect standing out by itself.

Having thus fully set forth and described this invention what is claimed is:

1. In a neon tube control apparatus, a power transformer, a secondary winding in said transformer, a pair of neon tubes connected in series with said secondary winding, a control switch having a rock shaft connected in said series circuit at a point between said neon tubes, a series of longitudinally spaced terminals on each of said neon tubes, contact arms on said rock shaft arranged to engage said terminals in a sequential manner, drive means for actuating said rock shaft, and a source of power for energizing said transformer and said drive means.

2. In a neon tube control apparatus, a power transformer, a secondary winding in said transformer, a pair of neon tubes, means for connecting one lead of said secondary winding to one end of one of said neon tubes, means for connecting the other lead of said secondary winding to one end of said other neon tube, a common lead interconnecting the other ends of said both of said neon tubes, a control switch having a rock shaft connected to said common lead, a series on longitudinally spaced terminals on each of said neon tubes, a series of contact arms carried on said rock shaft adapted to selectively engage said terminals on said neon tubes, and a source of power for actuating said rock shaft and energizing said transformer.

RICHARD E. DAVIES.
